US0D1105942S

(12) **United States Design Patent** (10) **Patent No.:** **US D1,105,942 S**
(45) **Date of Patent:** **** Dec. 16, 2025**

(54) **MASS SPECTROMETER**

(71) Applicant: **SHIMADZU CORPORATION**, Kyoto (JP)

(72) Inventor: **Masakuni Tachi**, Kyoto (JP)

(73) Assignee: **SHIMADZU CORPORATION**, Kyoto (JP)

(**) Term: **15 Years**

(21) Appl. No.: **29/905,401**

(22) Filed: **Oct. 20, 2023**

(30) **Foreign Application Priority Data**

Aug. 28, 2023 (JP) ..... 2023-017370 D

(51) **LOC (15) Cl.** **10-04**

(52) **U.S. Cl.**

USPC **D10/81**

(58) **Field of Classification Search**

USPC D10/70, 81, 83, 96, 84, 85, 65, 61, 74; D24/232, 186, 216, 231, 187

CPC G01N 15/00; G01N 15/10; G01N 15/14; G01N 15/1404; G01N 15/1436; G01N 15/1459; G01N 2015/0038; G01N 30/72; G01N 2030/027; G01N 5/00; G01N 7/00

See application file for complete search history.

(57) **CLAIM**

The ornamental design for a mass spectrometer as shown and described.

DESCRIPTION

FIG. 1 is a perspective view of a mass spectrometer showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
